A. MILLER.
DOOR OPERATING DEVICE.
APPLICATION FILED MAR. 22, 1916.

1,210,514.

Patented Jan. 2, 1917.

*Albert Miller,
inventor*

By Geo. Kimmel.

UNITED STATES PATENT OFFICE.

ALBERT MILLER, OF ROCHESTER, MINNESOTA.

DOOR-OPERATING DEVICE.

1,210,514.

Specification of Letters Patent.

Patented Jan. 2, 1917.

Application filed March 22, 1916. Serial No. 85,851.

To all whom it may concern:

Be it known that I, ALBERT MILLER, a citizen of the United States, residing at Rochester, in the county of Olmsted and State of Minnesota, have invented certain new and useful Improvements in Door-Operating Devices, of which the following is a specification.

The present invention relates to door operating devices and more particularly to automatic vehicle-operated means for controlling doors to buildings, gateways, and the like, and the primary object of my invention is to provide in a door operating mechanism of this character a simple, durable and effective structure for opening and closing the doors of a garage or the like, by the vehicle entering or leaving the garage.

Another object of my invention is to provide means for locking the doors or gates open or closed as the case may be.

A further object of my invention is to provide a door operating mechanism of the class described which may be applied to doors now in common use without the necessity of reconstructing the door or the building to which the device may be applied.

Of course, my invention may be readily applied to different uses but is particularly adapted for use in connection with automobile garages and the like.

Other objects and advantages to be derived from the use of my improved door operating mechanism will appear from the following detail description and the claims, taken with an inspection of the accompanying drawing, in which—

Figure 1 is a vertical sectional view taken through a building showing my improved door-operating mechanism applied thereto, a portion of the front wall being broken away to show the roadway tappet, Fig. 2 is a top plan view of my door-operating mechanism, the building having walls being shown in section, Fig. 3 is a longitudinal sectional view taken on the line 3—3 of Fig. 2, looking in the direction of the arrows, and Fig. 4 is an enlarged fragmentary elevational view of yieldable power-transmitting means which I employ, Fig. 5 is an end elevation of the catch block.

Referring more particularly to the draw-

ing, in which similar characters of reference designate like and corresponding parts throughout the various views, 1 designates the front wall of a building to which my invention is applied, the roof being designated 2 and side walls 3. The doors 4 and 5 are provided, and are hinged at 4' and 5' to swing outwardly in the present instance. 60

My invention more specifically contemplates the provision of means operable by a vehicle entering the building to open the doors 4 and 5, said means embodying opening and closing cables designated 6 and 7 65 respectively, said cables having connected therewith yieldable power-transmitting means comprising cylindrical members 8 and 9 described in detail hereinafter. The cables 6 and 7 are continued as at 10 and 11 and 70 are trained over sets of pulleys 12 and 13, the said cable 10 being trained over a pulley 14 and divided as at 15 to form a pair of oppositely extending lengths 16 and 17 for connection as at 18 and 19, respectively, with 75 arms 20 and 21 carried by the doors 4 and 5, respectively. As best shown in Fig. 2 the arms 20 and 21 extend inwardly and angularly from the doors and in view of this arrangement the provision of the sets of pulleys 12 and 13 hereinbefore described becomes necessary in order to bring the cables 10 and 11 into alignment with said levers. The lengths 16 and 17 of the cable 10 are trained beneath idlers 22 for an obvious purpose. 80 All of the pulleys 12, 13, 14 and the idlers 22 are mounted on the front wall of the building. The free end of the cable 11 is connected to the arm 20 at the point 18 hereinbefore set forth for a purpose which 85 will hereinafter appear. The cable section 17 is extended as at 23 and trained about an idler 25 mounted in a bearing bracket 26 on one of the walls 3 of the building. The free end of the section 23 is connected at 27 to 90 the cable 11. The free lower ends of the cables 6 and 7 are connected at 28 to a lever 29 mounted on a shaft 30, said shaft being mounted in bearings 31 and provided with a roadway tappet 32 having an anti-friction 100 roller 33. The lever 29 and roadway tappet are maintained normally in vertical position by a pair of coil springs 34 and 35. An idler 36 is provided to support the cable 7 in

the protecting housing 37. The top 38 of this housing is shown removed in Fig. 2. A pulley 39 is mounted in the housing 37 and the cable 6 is trained about said pulley to direct the proper pull on said cable when operating the device. Idlers 40 are provided for the cables 6 and 7 at the point at which the same leave the housing 37.

The yieldable power-transmitting means 10 designated generally 8 and 9 comprise tubular members having coil springs 41 mounted therein, said coil springs having one end thereof connected to the closed end-portion 42 of the tubular members and having the 15 opposite end portion thereof connected to a disk 43. The cables 6 and 7 are connected to the disks 43 and the cables 10 and 11 are connected to the tubular members 8 and 9. A block 44 is mounted on the wall 1 of the 20 building and secured in position by means of the screws or the like 45, for a purpose which will hereinafter appear. I provide means for maintaining the doors in open and closed positions, said means automatically operable by the vehicle entering or 25 leaving the building. The means for locking the doors open comprises a pair of pawls 46 pivoted at 47 to the front wall 1. The pawls are connected to a cable 48 by means 30 of extension cables 49 trained over pulleys 50, the cable 48 being trained over a pulley 51 and connected by a bracket arm 52 to a cable 7. The pawls 46 are provided with recesses 53 which are adapted to engage the 35 arms 20 and 21 when the doors are in open position.

The means for locking the doors in closed position comprises a rod 54 slidably mounted in brackets 55 on the front wall 1 of the 40 building, said arm having the lower end thereof bifurcated to provide engaging portions 56 receivable in brackets 57 carried by the doors. A cable 58 trained over pulleys 59 and connected by means of a bracket arm 45 60 to a cable 6 serves to disengage said arms 56 from the brackets 57 in a manner which will hereinafter appear.

In operation, the doors are normally in closed position as shown in the drawings, 50 and as a vehicle, in the present instance assuming it to be an automobile, approaches the door, one of the forward wheels thereof depresses the roadway tappet in a direction toward the doors. This swings the lever 30 55 and directs a pull on the cable 6. The sudden shock of the vehicle wheel striking the roadway tappet is absorbed by the spring carried in the yieldable power transmitting device 8. Upon the initial movement of the device 8. Upon the initial movement of the 60 roadway tappet the disk 43 of the power transmitting device 8 is moved downwardly until the peripheral edge thereof engages under the bottom marginal edge of the block 42. This retains the disk in the position 65 shown and the strength of the spring carried

by the member 8 exerts a pull on the cable 10, this pull being transmitted through the sections 16 and 17 to the arms 20 and 21 swinging the doors to open position. However, previous to this upon the initial movement of the roadway tappet the cable 58 has been moved, this movement raising the locking member 54 and permitting the doors to be opened in the manner set forth. When the doors have opened fully the pawls 46 75 engage the arms 20 and 21 retaining the doors in said position against the action of the coil springs 34 and 35. When the tubular sections of the power transmitting members 8 and 9 are drawn downwardly directing an operation to their lowermost positions their peripheral surfaces engage the block 42 disconnecting the disks from said block to permit return of the cables to normal position. When closing the doors the 85 roadway tappet is depressed in the direction opposite to the original movement thereof whereupon the cable 7 will be actuated and an operation identical with the foregoing will ensue. This operation is preceded by 90 the unlocking of the doors, that is, the pawls 46 are disengaged from the arms 20 and 21 permitting the doors to be moved to closed position. The doors are automatically locked by engagement of the locking member 54 95 with the brackets carried by the doors.

From the above description taken in connection with the accompanying drawings, it is thought that a clear and comprehensive understanding of the construction, operation and advantages of my invention may be had, and while I have shown and described my invention as embodying a specific structure, I desire that it be understood that I may make such changes on said structure as 100 do not depart from the spirit and scope of the invention as claimed.

What I claim as new and desire to secure by Letters-Patent is:—

1. In a device of the class described, a 110 pair of doors, arms carried thereby, an operating lever, a pair of cables connected therewith, said cables having their free ends connected with said arms, yieldable power-transmitting means in said cables, means for 115 engagement with said arms to lock the doors in open position, and means engageable with the doors for locking the same in closed position, both of said locking means being operatively engaged with said cables to render 120 said locking means at times inoperative.

2. In a device of the class described, power-transmitting means comprising a cylinder, said cylinder being connected to an object to be moved, a disk associated with 125 said tubular member and a spring for connecting the same thereto, said disk being connected with a source of power, and a block for engagement with said disk when said disk is distended under action. 130

3. In a device of the class described, an operating lever, a pair of cables connected thereto, said cables being operatively connected to a pair of doors to move the same to open or closed position, yieldable power-transmitting means interposed in said cables comprising tubular members, springs in said tubular members, disks connected with said

spring, a retaining block for engagement with said disk when said springs are dis- 10 tended under action, and means for locking said doors in open and closed positions.

In testimony whereof I affix my signature hereto.

ALBERT MILLER.
